[57] **ABSTRACT**

A wallpaper trimming guide is in the form of a shield having two flat flanges joined to define a corner for guiding a trimming knife or the like. The free edge of one of the flanges has a further flange at a right angle and provided with a hand-grip slot adjacent a similar slot in the one flange to define a secure hand grip.

FIG.1

FIG. 2

HAND TOOL FOR CLEAN CUTTING OF FIT-UP WALLPAPERS, FITTED CARPETS AND THE LIKE

The present invention relates to a hand tool for clean cutting of fit-up wallpapers, fitted carpets and the like.

By fitting up lengths of wallpaper on walls it is current to let the length hang down a bit over the floor ledge to enable fit of the same to the upper edge of the floor ledge. This is accomplished by cutting the length with a razor blade, a knife or a special cutting tool with a sharp blade which is held downwards during the cutting process. Consequently it often happens that one cuts down in the floor ledge or in electric wires, which in many houses are mounted on the upper edge of the floor ledge. Additionally, it is difficult to cut without support, which often has the consequence that the edge becomes ragged and sometimes also fringy.

The present invention aims to eliminate these disadvantages and relates to a hand tool which protects the floor ledge or the floor during the cutting process and furthermore enables a smooth cutting. The hand tool according to the present invention is generally characterized by a continuous and angularly bent shield with two flat and thin-walled sides of which one side is placed along that edge or that corner along which the wallpaper or carpet is to be cut, while the other side is placed under the wallpaper or carpet so that the shield forms a support for a cutting blade and its corner or one side forms a guide during the cutting process.

The invention will now be described with reference to the drawing in which

FIG. 1 is a perspective view illustrating a fit-up and uncut length of wallpaper with the hand tool placed in a functional position, and

FIG. 2 is a perspective view illustrating the length after the cutting process and with the hand tool in the same position.

According to the invention the hand tool consists of a shield 1, preferably of uncoloured plastic material to which wallpaper paste and the like is not likely to adhere. The screen 1 is angularly bent and forms two thin-walled sides 2 and 3 at right angle to each other. The shield is also so shaped that the sides 2, 3 merge in a relatively sharp corner 4. The shield 1 is additionally designed with some greater length than the width of a length of wallpaper 5 which is fit-up on a wall 6 with wallpaper paste or the like.

In order to get a firm grip during the cutting process, the shield 1 is provided with a handle. The handle consists of a flange 7, which extends from one side 2 of the shield 1 and is parallel with the other side 3. The flange 7 is provided with a recess 8 in which a hand can be put. Moreover, the side 2 is also provided with a recess 9 of about the same dimension and this recess is placed just opposite the recess 8 of the flange 7 whereby the user obtains a grip of the flange 7 and the side 2.

For a clean cut of the wallpaper 5, the shield 1 is

placed with the side 2 directly against the upper edge of a floor ledge 10 or eventually on electric wires 11 mounted on the upper edge of the same. The shield 1 is additionally placed with the side 3 against the wall 6 and under the wallpaper 5, whose end then will lie on the shield 1 (FIG. 1). After placing the shield 1, the length is preferably pressed in to the corner 4, so that it is lying close to the sides 2 and 3.

The shield 1 provides guidance and forms a level support for all kinds of cutting tools (not shown), e.g., razor blades, knives and especially designed tools, so that the length 5 can be cut at the exact right place and provided with a smooth edge. A very simple and safe way to cut the length 5 is obtained if the blade is pressed into the corner 4, since the corner 4 itself is a satisfactory guide. A length 5, cut according to this method, is shown in FIG. 2. However, if one intends to cut off a smaller edge of the length 5, the blade is placed against that part of the length which lies on the side 2, while the hand, a finger or a part of the cutting tool is placed against the side 3 (and that part of the length which is placed against that side) during the cutting process, which means that the side 3 is used as guiding-side for obtainment of an edge, exactly parallel with but spaced from the corner 4. Additionally it is possible to provide a graduation (not shown) on the tool or the shield 1, to indicate where the length shall be cut.

The shield 1 according to the description is only described for side cutting of lengths of wallpaper for their adjustment to a floor ledge, but it can also be used for adjustment of lengths to a floor or a roof, and thereto useful for side cutting of fitted carpets.

The hand tool according to the description is especially useful in professional hanging, but since the tool has a very simple structure which exclude incorrect handling, it can be used also by non-professionals.

The invention is not limited to the described embodiment, but can be varied within the scope of the appended claims. Thus, the shield side 2 can be provided with an especially smooth surface layer or an agent can be brought on the same, so that the cut-off wallpaper strip is easy to remove from the tool.

What we claim is:

1. A device for use in trimming a surface covering sheet material, said device having right angularly related flat walls meeting at a corner, one of said walls being adapted to be placed under an edge of said sheet material with the other wall projecting outwardly from said surface with said corner serving as a guide for a cutting tool, said other wall having a laterally extending flange at its free edge and said flange and said other wall each having a slot therethrough with said slots arranged to receive the fingers of a user's hand and serve as a handle for gripping and manipulating said device.
